The ornamental design for a golf cap, as shown and described.

DESCRIPTION

FIG. 1 is a perspective view of the golf cap according to the present invention showing several golf tees, a green repair tool and a ball marker mounted on the underside of the bill of the cap;

FIG. 2 is a front elevation view thereof;

FIG. 3 is a rear elevation view thereof;

FIG. 4 is a side elevation view thereof;

FIG. 5 is a side elevation view, thereof, viewed from the side opposite FIG. 4;

FIG. 6 is a top plan view thereof; and,

FIG. 7 is a bottom plan view thereof.

The broken lines showing the golf tees, repair tool and ball marker in FIGS. 1, 2, 3, 4, 5 and 7 are for illustrative purposes only and form no part of the claimed design. The other broken lines represent stitching.
